US00D956986S

(12) United States Design Patent (10) Patent No.: US D956,986 S
Cai (45) Date of Patent: * Jul. 5, 2022

(54) SONIC DIAMOND MICRODERMABRASION MACHINE

(71) Applicant: GUANGDONG NEWDERMO BIOTECH CO., LTD, Guangzhou (CN)

(72) Inventor: Qingyao Cai, Guangzhou (CN)

(73) Assignee: GUANGDONG NEWDERMO BIOTECH CO., LTD, Guangzhou (CN)

() Term: 15 Years

(21) Appl. No.: 29/766,978

(22) Filed: Jan. 20, 2021

(30) Foreign Application Priority Data

Dec. 8, 2020 (CN) 202030753438.3

(51) LOC (13) Cl. 28-03

(57) CLAIM

The ornamental design for a sonic diamond microdermabrasion machine, as shown and described.

DESCRIPTION

FIG. 1 is a perspective view of a sonic diamond microdermabrasion machine showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the sonic diamond microdermabrasion machine that form no part of the claimed design.

1 Claim, 8 Drawing Sheets
